CLAIM

The ornamental design for a drinking cup set, as shown and described.

DESCRIPTION

FIG. 1 is a perspective view of the drinking cup set of the invention;

FIG. 2 is an exploded perspective view thereof;

FIG. 3 is a front exploded view;

FIG. 4 is a rear exploded view;

FIG. 5 is a left side exploded view, the right side exploded view being a mirror image thereof;

FIG. 6 is a top exploded view; and,

FIG. 7 is a bottom exploded view.

The broken lines in the drawings are included for the purpose of illustration and form no part of the claimed design.
